Filed Nov. 13, 1962, Ser. No. 72,464

Term of patent 14 years

(Cl. D71—1)

FIGURE 1 is a side elevational view of an outboard propulsion unit, showing our new design;

FIGURE 2 is a rear elevational view thereof; and

FIGURE 3 is a top plan view thereof.

The transom shown in broken lines is included for illustrative purposes only.

The dominant features of our design reside in the portions shown in full lines.

The side not shown is a mirror image of the side shown.

We claim:

The ornamental design for an outboard propulsion unit, substantially as shown and described.
